UNITED STATES PATENT OFFICE.

RANDOLPH F. HAGEMAN, OF NEW MADISON, OHIO.

AUTOMATIC GATE.

SPECIFICATION forming part of Letters Patent No. 251,870, dated January 3, 1882.

Application filed November 23, 1881. (No model.)

To all whom it may concern:

Be it known that I, RANDOLPH F. HAGEMAN, a citizen of the United States, residing at New Madison, in the county of Darke and State of Ohio, have invented certain new and useful Improvements in Gates, of which the following is a specification, reference being had therein to the accompanying drawings.

My invention relates to gates; and it consists of the construction and arrangement of its several parts, as will be hereinafter fully set forth.

In the drawings, Figure 1 is a side elevation. Fig. 2 is a top-plan view of my gate, and Fig. 15 3 is a side elevation of the latch-post.

A is the gate. It is of ordinary construction, and is hinged to the pivot-post B, as shown. It has a rigid latch, a, upon its swinging end, which engages with a pivoted latch, c, on the 20 latch-post C.

The gate-frame consists of the pivot-post B, the latch-post C, and the base-boards D D, between the ends of which the posts are securely fastened, as shown.

Attached to the bottom of the hinge-post of the gate is a rigid crank, E, as shown. Pivoted upon a block, d, between the base-boards, is a reciprocating lever, F, and journaled in the upper edge of said base-boards, and immediately in front of the latch-post C, is a rock-shaft, G, which has pedals g g secured to their outer ends, as shown. Depending from the lower side of this lever G is an arm, g', and pivoted to it is a rod, c', which has its upper 35 end pivoted in the rear end of the latch c, as shown.

Pivoted in the lower end of the arm g', and to one end of the lever F, is a lever, f, and extending from the other end of the lever F to 40 the end of the rigid crank E is the lever f', as shown.

In the operation of the mechanism the foot

is placed upon either of the pedals g and the end g pressed downwardly, which will cause the arm g' and lever f and the end of the lever 45 F, to which it is attached, to be carried forward. This action will draw the lever f' and crank E inwardly, thus forcing open the gate. The forward movement given the arm g' will operate to force the latch-arm c' upwardly, carrying with it the rear end of the pivoted latch c, which will, of course, lower the front end, free the rigid latch a in the gate, and allow it to swing open by the operation of the other levers, as shown. 50

What I claim is—

1. In a gate, the combination of the rock-shaft G and its downwardly-extending arm g', journaled horizontally between the base-boards D, with the vertically-acting connecting-rod c', 60 having its lower end pivoted to the arm g' and its upper to the rear end of the pivoted latch c, all arranged to operate as shown and described.

2. The combination of the horizontal rock-shaft G, its pedals g, and downwardly-extending arm g', journaled between the base-boards D, with the connecting-rod f, reciprocating lever F, rod f', and crank E, secured to the lower end of the pivot-post of the gate, all 65 arranged and operating as set forth. 70

3. In a gate, the rock-shaft G, provided with operating-pedals g, and a downwardly-projecting arm g', to which is pivoted the vertical connecting-rod c' and horizontal rod f, said rock-shaft being adapted to open and close the gate 75 and to release the latch by means of the connecting mechanism, as hereinbefore described.

In testimony whereof I affix my signature in presence of two witnesses.

RANDOLPH F. HAGEMAN.

Witnesses:

J. H. BANKS,
I. F. S. HAGEMAN.
